ROLL GAUGE FOR GAUGING EXTERNAL SCREW THREADS

Jacob H. Niper, Hackettstown, N. J.

Application July 8, 1947, Serial No. 759,680

3 Claims. (Cl. 33—199)

(Granted under the act of March 3, 1883, as amended April 30, 1928; 370 O. G. 757)

1

The invention described herein may be manufactured and used by or for the Government for governmental purposes without the payment to me of any royalty thereon.

This invention relates to an adjustable gage to check external screw threads.

The object of this gage is to provide a means of quickly and accurately checking the pitch diameter of external screw threads at a minimum of expense. This it accomplishes by being adjustable over a wide range of diameters with only minor adjustments necessary when changing from one diameter to another and by being adjustable over a wide range of thread pitches through the changing of the rollers from one pitch to another.

Figure 1 is a left side view of the gage showing the top roller lowered into gaging position.

Figure 2 is a front view of the gage showing the top roller lowered into gaging position.

Figure 3 is a top view of the gage.

Figure 4 is an end view of the top roller.

Figure 5 is a sectional view of the top roller taken on line 5—5 of Fig. 4.

Figure 6 is a sectional view of the top roller taken on line 6—6 of Fig. 4.

Figure 7 is a sectional view of one of the two bottom rollers.

1 is a base which supports the gage and may be provided with four holes 2 with which to fasten it to the inspection table. 3 is a marking disc, held in position by screw 4, on which may be stamped the size of the rollers being used in the gage. 5 are the bottom roller supports, which with the axles 6, and axle screws 7, hold the bottom or backing rollers 8 and 9. 10 is a cylindrical surface, extending from the end to the edge of the first ridge on roller 8, whose length is relative to a like surface of different length on roller 9, the lengths of these surfaces being calculated to prevent the insertion of the piece being checked into the gage in such a manner as to "cross" the threads. By reversing the positions of pieces 8 and 9, left hand threads may be checked.

A post 11, provided to support the indicator 12 and top roller 13, is anchored to the base 1 by a key 14 and screw 15.

The indicator 12 and top roller 13 are carried on a plate 16, which is clamped to post 11 by a locking screw 17 and locking bushings 18, and prevented from rotating about the post by key 19. The indicator 12 and top roller 13 are connected by a shaft 20 riding through a hardened bushing 21, which is pressed in plate 16. This shaft is prevented from rotating by a screw 23 threaded in plate 16 and having its end engaged in a key way 22 in and extending longitudinally of shaft 20. Indicator 12 has a lug 12a extending from the back of its casing and having a smooth fit within the slotted upper end of shaft 20. A pin 12b passes through aligned apertures in the lug and shaft to secure the indicator to the shaft.

2

Rotation of the indicator relatively to the shaft is prevented by a locking pin 12c. A yoke 20a is fixed to the lower end of shaft 20. The lower ends of the arms of this yoke have aligned bores in which a shaft 26 is fixed by screws 27. Top roller 13 is journaled on shaft 26.

A coil spring 28 surrounds shaft 20 between yoke 20a and plate or bar 16 and acts to urge upper roller 13, yoke 20a and shaft 20, downwardly. A second coil spring 29, more powerful than 28, encircles the upper portion of shaft 20 between plate 16 and a collar 30. The collar 30 is slideable on and along shaft 20. Downward sliding movement of collar 30, to compress spring 29, is effected by wires or links 33 secured to respective opposite sides of collar 30 at their top ends, as clearly shown upon Figure 2. The lower ends of the wires or links are attached to the respective arms of a bail or yoke 32. The ends 20 of these arms are pivoted to bar 16 by screws 34. Upward or counterclockwise pivotal movement of bail 32, as viewed in Figure 1, is limited by a pair of aligned stop pins 35 fixed in bar 16. Upward sliding movement of collar 30 relatively 25 to shaft or rod 20 may be stopped by engagement of the collar with the casing of indicator 12. Since spring 29 is stronger than 28, when bail 32 is released, collar 30 moves upwardly relatively to shaft 20 until the collar engages the casing of indicator 12. Thereafter, spring 29 acts against, and overpowers, spring 28 to move the indicator, shaft 20 and gage roller 13, as a unit upwardly. When bail 32 is grasped and pivoted downwardly, spring 29 is compressed, as shown in Figure 1, and 30 shaft 20 and indicator 12 are freed for downward movement under the thrust of spring 28 until roller 13 contacts a specimen to be gaged. By this feature, the roller contacts successive specimens with the same force, and variations otherwise caused by the "personal equation" due to different gaging forces, are eliminated and more accurate gaging is effected.

The indicator 12 is of the conventional single or offset contact type having a scale 41 and cooperating pointer 42 connected with a contact 37 in any known manner for actuation thereby. Contact 37 is resiliently pressed by the gage mechanism, against a block 38 fixed on plate 16. Since the plate is rigidly fixed to standard 11, slight movements of shaft 20 and roller 13, up and down, through plate 16, cause a greatly magnified movement of pointer 42 over scale 41.

Figure 4 is an end view of the top roller 13. As can be seen in Fig. 4, one half of the roller is larger than the other. This is done to create two width of crests 39 and 40 on the ridges as shown in Figs. 5 and 6. The larger diameter is such that it will create a crest 39 whose width is equal to the width of the maximum sized root of an acceptable thread of a given pitch. The smaller diameter is such that it will create a crest 40 whose width is a little greater than the width of

the maximum sized root of an acceptable thread of a given pitch. The reason for this type of roller is explained hereinafter.

To facilitate manufacture the bottom rollers may be made with every other ridge omitted as shown in Fig. 7. The form of the ridges in both the top and bottom rollers corresponds to the form of the thread being checked. The ridges on the rollers are annular in design.

To adjust this gage it is necessary to insert the proper set of rollers for the pitch of the thread being gaged, place the "go" check plug in position between the rollers, adjust the position of the rollers, pull down on the bail 32 and identify or note the corresponding position of the dial hand 42 of the indicator 12. The "no go" check gage is then substituted for the "go" check gage and the corresponding position of hand 42 again noted or identified in any known manner, to thereby determine a permissible range of movement or tolerance between the two positions.

In operating this gage the piece being checked is placed on the bottom rollers, the handle 32 pulled down and the piece revolved. If during this revolving the dial hand 42 of the indicator 12 remains within the range of movement previously determined, the thread on the piece is within its limits.

The top roller is made with two different width crests, Figs. 4 and 5, to prevent accepting threaded parts with a pitch diameter that is under the minimum allowable size. Should the minor diameter of the thread of the specimen being tested, be at its maximum allowable size and its pitch diameter be undersize, when the part of the upper roller with the narrower crests of the ridges 39 is riding in the thread of the specimen the indicator will show the thread as being acceptable, but when the juncture between the different sized crests is passed there will be a sharp change in the indicator reading, showing that the gage had been riding on the minor and not the pitch diameter of the specimen thread and therefore that the part should be rejected.

I claim:

1. In a screw thread gaging instrument, a normally horizontal base, first and second ridged backing rolls, means mounting said rolls on said base on normally horizontal, horizontally-spaced parallel axes, a post fixed to said base and rising therefrom, a plate carried by said post for vertical adjustment therealong, a normally vertical shaft mounted upon said plate for axial translation only in a normally vertical plane between and parallel with the axes of said backing rolls, a dial indicator having an actuating contact and fixed to the upper end of said shaft, a third threaded gaging roll journaled upon the lower end of said shaft for movement with said shaft and gage in a first direction toward said backing rolls, first spring means urging said shaft in said first direction, second spring means stronger than said first spring means and adapted to urge said shaft in a second direction opposite to said first direction, and means pivoted on said plate and manually operable to compress said second spring means to free said shaft completely to the action of said first spring means, the actuating contact of said dial indicator contacting said plate for operation by relative vertical translation of said shaft relatively to said plate.

2. In a single or offset contact gaging instrument, a base, a pair of backing rolls mounted on

said base on horizontally spaced axes, a column fixed in and rising from said base, a plate fixed on said column above said base, a shaft carried by said plate for axial translation only toward and from said backing rolls, a gaging roll mounted on the lower end of said shaft for gaging coaction with said backing rolls, a single contact dial indicator fixed on said shaft and having its operating contact yieldingly engaging said plate for operation by relative translation of said shaft and plate, a first coil spring acting between said plate and shaft to urge the latter downwardly and move said gaging roll toward said backing rolls, a collar slidably mounted on said shaft, a second spring stronger than said first spring and interposed between said collar and plate, manually operable bail means carried by said plate, and a connection between said bail means and collar to slide the latter, in response to operation of said bail means and thereby compress said second spring and free said shaft and dial indicator to the action of said first spring.

3. In a screw thread gaging instrument, a normally horizontal base, first and second ridged backing rolls, means mounting said rolls on said base on normally horizontal, horizontally-spaced parallel axes, a post fixed to said base and rising therefrom, a plate carried by said post for vertical adjustment therealong, a normally vertical shaft mounted upon said plate for axial translation only in a normally vertical plane between and parallel with the axes of said backing rolls, a dial indicator having an actuating contact and fixed to the upper end of said shaft, a third threaded gaging roll journaled upon the lower end of said shaft for movement with said shaft and indicator in a first direction toward said backing rolls, first spring means urging said shaft in said first direction, second spring means stronger than said first spring means and adapted to urge said shaft in a second direction opposite to said first direction, and means pivoted on said plate and manually operable to compress said second spring means to free said shaft completely to the action of said first spring means, the actuating contact of said dial indicator contacting said plate for operation by vertical translation of said shaft relatively to said plate, said first and second spring means each comprising a compression coil spring surrounding said shaft below and above said plate, respectively, said manually operable means comprising a bail pivoted on said plate, a collar slidable on said shaft above said second spring, and operating connections between said bail and collar.
